DESIGN FOR A COAT

Israel Yellin, New York, N. Y.

Application July 7, 1936, Serial No. 63,690

Term of patent 3½ years

To all whom it may concern:

Be it known that I, Israel Yellin, a citizen of the United States of America, residing in Manhattan, county of New York, and State of New York, have invented a new, original, and ornamental Design for a Coat, of which the following is a specification, reference being had to the accompanying drawing, forming part thereof, wherein,

Figure 1 is a front view of a coat showing my new design.

Figure 2 is a rear view of the coat shown in Figure 1.

The characteristic feature of my design resides in the collar portion of my coat, having a two piece stationary collar which extends to the side front with flared rippled revers in combination with the coat, as shown.

I claim:

The ornamental design for a coat, substantially as shown and described.

ISRAEL YELLIN.
